UNITED STATES PATENT OFFICE.

WILLIAM J. GRINDEN, OF BROOKLYN, NEW YORK, ASSIGNOR TO J. H. WILLIAMS & CO., OF SAME PLACE.

DESIGN FOR A BICYCLE-CRANK.

SPECIFICATION forming part of Design No. 23,640, dated September 11, 1894.

Application filed August 10, 1894. Serial No. 519,978. Term of patent 7 years.

To all whom it may concern:

Be it known that I, WILLIAM J. GRINDEN, a citizen of the United States, residing at Brooklyn, in the county of Kings and State of New York, have invented a new Design for a Bicycle-Crank, of which the following is a specification.

The leading feature of this design for a bicycle crank consists in the shape of the crank with rounding ends and tapering shank grooved longitudinally, the ends of the grooves being rounding.

In the drawings:—Figure 1. is a side view of a bicycle crank, showing my design, and Fig. 2. is a cross section of the same, at the line x . x .

The ends a . and b . of the crank are rounding and the shank is tapering and grooved at c . c . so that the section of the shank is similar to a cross as seen in Fig. 2. and the ends of the grooves are rounding as shown.

I claim—

The design for a bicycle crank substantially as described and shown.

Signed by me this 3d day of August, 1894. 25

WM. J. GRINDEN.
